Fig. 4

Fig. 5

FIGURE 1 is a perspective view of a strap support for a pair of spectacles, showing my new design;

FIGURE 2 is a front elevational view thereof;

FIGURE 3 is a side elevational view thereof, the other side not shown being the mirror image of the side shown;

FIGURE 4 is a rear elevational view thereof; and

FIGURE 5 is a transverse sectional view taken along line 5—5 in FIGURE 3.

The broken line showing of the spectacles in FIG. 1 is for illustrative purposes only.

I claim:

The ornamental design for a strap support for a pair of spectacles, substantially as shown and described.
